UNITED STATES PATENT OFFICE.

LAWRENCE F. KENNEDY, OF ST. PAUL, MINNESOTA.

GUN-STOCK.

1,266,024.

Specification of Letters Patent. Patented May 14, 1918.

Application filed October 10, 1914, Serial No. 866,067. Renewed August 29, 1917. Serial No. 188,872.

To all whom it may concern:

Be it known that I, LAWRENCE F. KENNEDY, a citizen of the United States, residing at St. Paul, in the county of Ramsey 5 and State of Minnesota, have invented certain new and useful Improvements in Gun-Stocks, of which the following is a specification.

My invention relates to gun-stocks and 10 has for its object to provide a gun having a telescopic sight and a resilient recoil pad with means permitting the housing of said telescopic sight within the gun-stock when not in use.

15 For high-powered rifles such as are used by armies and for other purposes both a telescopic sight and a recoil pad are requisite, the former to enable the shooter to see the target at a great distance so as to properly direct the fire of the gun; the other to receive the impact of the severe recoil which accompanies the shooting of such a high-powered rifle to protect the shoulder from serious injury. It is impractical and unsatisfactory to have the telescopic sight continually mounted upon the rifle, both because of the inconvenience entailed and because of the liability of injuring the telescope and rendering the same ineffective.

20 Also, recoil pads as heretofore employed have completely sealed the butt end of the gun-stock making it impossible to house the telescope within the butt of the gun. It is the object of my invention to provide a true

25 telescoping spy-glass for sighting purposes which, when in use, can be accurately adjusted for the longest ranges, but which may be removed from its operative position and closed up into a comparatively small bundle

30 which may be housed within an opening in the gun-stock and to provide a recoil pad in combination with said housing for the telescope, which, while effective to completely cover the butt end of the gun-stock, will,

35 nevertheless, permit convenient access to said housing. It is also an object of my invention to provide a recoil pad member having such a mounting that the same may readily be substituted for the butt plate ordinarily applied to the end of a rifle stock

40 without the necessity of any modification of the rifle stock.

45 The full objects and advantages of my invention will appear in connection with the detailed description thereof and are particularly pointed out in the claims.

In the drawings, illustrating the application of my invention in one form,—

Figure 1 is a side view of a portion of a rifle having my improvements connected therewith and showing the telescopic sight in operative position. Fig. 2 is a side sectional view of a portion of a gun-stock having my improvements connected therewith and showing the telescope closed up and housed within the gun-stock. Fig. 3 is a fragmentary sectional view of the end of the gun-stock showing the recoil pad in position for permitting access to the telescope housing. Fig. 4 is a view of the reverse side 70 of the butt to that shown in Fig. 1 with the recoil pad in closed position. Figs. 5 and 6 are transverse sectional views of the end of the gun-stock showing the recoil pad member in open and closed position, respectively. 75

As illustrated, the stock 10 of the rifle may be provided with a plurality of longitudinal cavities or housings 11 and 12, respectively, which housings open through the end of the stock, as indicated at 13 in Figs. 3, 5 and 6. 80 A spy-glass 14 for sighting purposes, comprising a series of telescoping sections, is shown in Fig. 1 mounted in operative position upon adjustable rests 15 and 16. In Fig. 2 the spy-glass 14 is shown in closed 85 condition within the housing 11. The recoil pad member comprises a butt plate 17 which has a flange member 18, said butt plate being secured to the gun-stock by a screw 19 extending through the butt plate 90 proper and another screw 20 extending through the flange 18. The butt plate is provided with a pair of circular apertures 21 and 22 above the openings 13 from cavities 11 and 12. The openings 21 and 22 are 95 closed by a swinging gate 23 having expanded portions 24 and 25 which exactly fit within said openings. Said gate is hinged at 26 to the plate 17, having a squared head 27 by which, through the action of a spring 28, the gate 23 is held in open or closed position. A tongue 29 on the gate 23 extends slightly beyond the end of the flange portion 18, by which means the gate is readily opened. 100

105 The recoil member also comprises a wooden piece 30 hollowed out, as indicated at 31. The piece 30 has connected thereto a hinge plate 32 which has thereon lugs 33 co-operating with a hinge extension 34 on plate 17, 110 so that by means of a pin 35 the piece 30 is hingedly connected to the butt plate 17 so

as to swing open sidewise along the same, being held in open position, as indicated in Fig. 5, by the lugs 33 and pin 35, and when closed having said lugs flush with the side 5 of the gun-stock, as best shown in Figs. 4 and 6. A catch 36 is adapted to take under the edge of plate 17 in a cavity 37 in the end of butt 10, as best shown in Fig. 6, said catch being secured to a spring 38 and oper- 10 able to be released by a button 39 on a pin 40 secured to said catch and extending through the wall of piece 30, the spring 33 being secured to the inner wall of said piece 30 within the cavity 31. Securely cemented 15 to the piece 30 so as to have the walls thereof flush with the outer edges of said piece, which walls are shaped to continue the outline of the gun-stock so as to completely close the opening 31, is a resilient pad 41, 20 which may be made of any desired resilient material, a somewhat soft and spongy rubber being effective for the purpose. If desired, this pad may be partially cut out or thinned above the opening 31 in the piece 25 30, as indicated at 42 in Fig. 6.

The operation of my invention will be apparent. When it is desired to use the telescopic sight, the recoil pad member 30 is swung open on its side hinge and the gate 30 23 is lifted, as indicated in Fig. 3. The closed telescope 14 is then withdrawn from the housing 11 and secured in operative position to the rifle, as indicated in Fig. 1, the gate 29 and member 30 being closed in the 35 position indicated in Figs. 1, 2 and 4. The piece 30 makes a closed contact with the surface of the plate 17 so that when the same is in closed position the chamber 31 is practically sealed from the outside air. When 40 the rifle is shot there is added, therefore, to the natural resiliency of the pad 41 the cushioning effect of the imprisoned air in the chamber 31, which has the result of effectually absorbing the shock of the recoil 45 so that practically none of such shock is transmitted to the shoulder of the shooter. When the use of the telescopic sight is no longer necessary, either because the gun is not being shot, or because the range is not 50 great enough to require it, the telescope 14 may be quickly removed and closed up and inserted within the housing 11, the members 30 and 29 being readily raised for that purpose. Both of these members can be opened

and closed by a gloved or mittened hand, it 55 being only necessary to engage the button 39 and the tongue 29 for that purpose. The cavity or housing 12 may be employed for the reception of a thong case and oiler, which, of course, may be withdrawn and re- 60 turned with the same facility as the telescope 14.

I claim:

1. In combination with a gun having a chamber in the stock opening through the 65 butt end thereof, a metallic butt plate secured to the end of said stock and having a gate opening into said chamber, a recoil absorbing member, and means securing said member to the butt plate in such manner 70 that the member may be removed from in front of the gate to permit opening thereof.

2. In combination with a gun having a chamber in the stock opening through the 75 butt end thereof, a metallic butt plate se- 75 cured to the end of said stock and having a gate opening into said chamber, and a recoil absorbing member including a resilient recoil pad hingedly connected to said metallic plate.

3. In combination with a gun having a chamber in the stock opening through the 80 butt end thereof, a metallic butt plate se- 80 cured to the end of said stock and having a gate opening into said chamber, a recoil ab- 85 sorbing member including a resilient recoil pad connected by means of inset hinges with said metallic plate, and means for locking said recoil member in closed position to form a butt-end continuation of the gun-stock. 90

4. In combination with a gun having a chamber in the stock opening through the 95 butt end thereof, a metallic butt plate secured to the end of said stock and having a gate opening into said chamber, a recoil absorb- 95 ing member comprising a wooden piece shaped to form a continuation of the gun- stock and hingedly connected with said metal plate, and a resilient pad secured to said piece and forming the butt end of the 100 gun.

In testimony whereof I affix my signature in presence of two witnesses.

LAWRENCE F. KENNEDY.
